COAT

Benjamin C. Hillson, Brooklyn, N. Y., assignor to
 Rough Wear Clothing Co., New York, N. Y., a
 corporation of New York

Application April 7, 1936, Serial No. 73,063

4 Claims. (Cl. 2—93)

This invention relates to improvements in coats and more particularly to a coat having a built-in muffler.

One of the main features of the invention resides in a coat wherein the use of a separate muffler to protect the chest and neck of a wearer is eliminated. For this purpose, I employ a muffler secured to the inside of the coat which when in use with the coat buttoned at the front, imparts to the wearer the appearance that he is wearing a conventional style muffler.

Another feature of the invention is to provide a muffler which is permanently attached to a coat for use as such when the occasion arises, and which may be flatly folded to a concealed position inside of the coat when not in use without producing a bulky appearance.

A further feature of the invention is the provision of a permanently attached muffler for coats in which the back of the muffler may remain upstanding with the remainder of the muffler folded inwardly for protecting the neck and collar of a wearer against soiling by contact with the folded portion of the fold over collar of the coat.

A still further object of the invention is to provide a coat having a muffler feature which does not materially increase the cost of manufacture over that of the coat alone.

Other objects of the invention will appear in the following specification when read in conjunction with the accompanying drawing, in which:

Figure 1 is a front perspective view of a man wearing my improved coat, the front of the coat being spread open to reveal the buttoned muffler.

Figure 2 is a fragmentary side elevational view with the muffler and coat buttoned.

Figure 3 is a view similar to Figure 2 but showing the chest portion of the muffler folded inwardly of the coat and with a portion of the coat broken away.

Figure 4 is an enlarged vertical sectional view through the fold over collar of the coat showing the muffler in position for use.

Figure 5 is a view similar to Figure 4, but showing the muffler folded inwardly of the coat when not in use.

Figure 6 is a fragmentary inside plan view of the collar portion of the coat with the muffler sections in outfolded position for use, the dotted lines indicating one of the muffler sections when folded inwardly to non use position.

Whereas my muffler may be embodied in all styles of coats, the same is primarily adaptable for use upon leather coats used for work or sport wear, for in such construction of coats it is most

uncomfortable for the wearer to turn up the leather collar to protect his chest and neck from cold and inclement weather, for it is well known that leather is cold to the touch. Furthermore, contact of the leather fold-over collar with the skin or shirt collar of a wearer results in soiling the skin or shirt collar for the color or dirt from the leather collar easily rubs off. By the use of my built-in muffler, the desired neck and chest protection is available, and therefore it is unnecessary for a wearer to resort to the turning up of the fold-over leather collar when such occasion may arise.

Referring to the drawing by reference characters, the numeral 10 designates a coat which may be of the jacket or full length style. The exterior of the coat in this instance is constructed of leather or imitation leather 11, while the inside thereof is provided with a fabric lining 12.

The body of the coat is designated 13 and is provided with a fold-over collar 14 and lapels 15—15, the outer face of the collar and lapels being leather. The collar 14 is joined to the body 13 along the seam 16, but as shown in Figures 4 and 5, the rolled fold 17 of the collar is beyond the seam 16 when the coat is in position upon a wearer.

The muffler includes two fabric muffler sections 18 and 19 which may be constructed of flannel, wool, or the like. The muffler sections 18 and 19 are identical in construction so that a description of one will suffice for the other.

Each muffler section includes a substantially straight attaching edge 20, an opposed curved neck line edge 21, and a substantially straight front edge 22, which latter edge forms a continuation of the neck line edge 21. Inwardly of the front edge 22, the muffler section is provided with a row of buttons 23, while button holes 24 are provided adjacent the edge 22 of the muffler section 19. The edges of the muffler sections may be provided with a tape binding as illustrated in the drawing.

The muffler sections 18 and 19 are secured to the inside of the coat with the attaching edges 20 in outwardly diverging relation, the inner or tail end 25 of the same freely overlapping at the central portion of the fold-over collar 14 as best seen in Figure 6 of the drawing. A continuous line of stitching 26 extends parallel to the attaching edges 20 of the two muffler sections 18 and 19 and serves to secure the muffler sections in a flap-like manner to the inner lining 12 of the coat body. The outer ends of the muffler

sections terminate adjacent the lower ends of the respective lapels 15.

In practice, when the coat 10 is in position upon a wearer as shown in Figures 1 and 2 of the drawing, the muffler sections 18 and 19 are drawn forward about the wearer's neck with the neck line edges 21 snugly fitting about the neck. This causes the front edges 22 of the muffler sections to be disposed vertically in overlapping relation at the front of the wearer and permits the muffler sections to be secured together by passing the buttons 23 through the respective button holes 24. When the coat 10 is buttoned up, the muffler serves as a protection against the elements both at the front and about the neck of the wearer, thus making it unnecessary for the collar 14 and lapels 15 to be turned up to obtain such protection. The rear neck portions of the muffler sections extend upwardly to a position slightly above the roll 17 on the collar to prevent rubbing contact of the collar with the neck or shirt collar of the wearer.

Should it not be desired to protect the chest of a wearer, the front portions of the muffler sections may be folded back on the inside of the coat as shown in Figure 3 while the rear or tail ends of the muffler sections are left standing to protect the back of the neck and shirt collar from becoming soiled by rubbing contact with the coat collar 14. This is advantageous when the muffler is embodied in leather work or sport coats. Should it be desired to dispense with the entire use of the muffler, the muffler sections 18 and 19 may be folded their entire length inwardly along the stitching line 26, the muffler section 18 being so shown in dotted lines in Figure 6 of the drawing. When the two muffler sections are folded inwardly of the body of the coat, the same lie flat, for the free lapping of the tail ends 25 overcomes any buckling thereof. The line of stitching 26 at the tail ends 25 of the muffler sections is disposed inwardly of the seam 16 so that when the muffler sections are folded to non use position, the presence of the muffler within the coat cannot be detected, and the presence thereof does not in any way interfere with the comfort of the wearer or with the lie of the fold-over collar of the coat.

While I have shown and described a button and button hole connection between the two muffler sections for securing the same together, it will be understood that snap fasteners or other analogous fastening devices may be employed in lieu thereof.

Although I have shown and described one specific embodiment of my invention, I do not

wish to limit myself thereto, for such changes and alterations as come within the scope of the appended claims may be resorted to if desired.

Having thus described the invention, what I claim as new and desire to secure by Letters Patent is:—

1. In a coat having a body and a collar attached thereto, a muffler comprising a pair of muffler sections secured to the inside rear of said body adjacent said collar, said muffler sections 10 having inner ends which freely terminate against the back of the collar, and said muffler sections being successively foldable outwardly to a position to protect the neck and chest of a wearer when the coat is in use, or to an infolded concealed position relative thereto, and fastening means for securing the muffler sections together at the front of said coat when the muffler sections are in out folded position.

2. In a coat having a body and a collar attached thereto, a muffler comprising a pair of muffler sections secured along one of their edges to said body adjacent said collar, the muffler sections having inner ends which terminate substantially at the back of the collar in free overlapping relation, said muffler sections being outwardly foldable to muffler forming position to extend about the neck of a wearer and to lie over the wearer's chest when the coat is in use, and fastening means for securing the front portions of the muffler sections together.

3. In a coat having a body and a foldover collar attached thereto, a muffler comprising two separate muffler sections stitched along one of their edges to said body and having inner ends which terminate substantially at the back of the collar in free overlapping relation, said muffler sections adapted to be brought forward about the neck of a wearer to overlie the chest when the coat is in use, portions of said muffler sections protecting the neck of a wearer from contact with the roll fold of the fold-over collar, and means for fastening the outer ends of the muffler sections together at the front of the coat.

4. In a coat having a body and a collar attached thereto, a muffler comprising two flap-like muffler sections stitched to said body, said muffler sections having inner ends which terminate adjacent the back of the collar in free lapping relation, whereby said muffler sections may be swung to a position for use about the neck and chest of a wearer, and flatly folded within said body when not in use, and fastening means for securing the front ends of said muffler sections together when they are in position for use.

BENJAMIN C. HILLSON.
